TEMPERATURE CONTROL UNIT

Gottlieb F. Zuckér, Chicago, Ill.

Application September 27, 1944, Serial No. 555,991

3 Claims. (Cl. 236—49)

1

This invention relates to temperature control units, and particularly to such units as adapted for use with refrigerator structures and systems.

It is an object of the invention to provide an improved temperature control unit or structure of simplified construction and operating characteristics. More specifically stated, it is an object of the invention to provide an improved and simplified temperature control unit or structure, whereby the passage of heat conducting fluids between a pair of thermally isolated chambers, one of which is adapted for control by the other, is controlled in accordance with temperature conditions prevailing respectively in said chambers, in a simplified and automatic manner.

A further object of the invention is to provide an improved temperature control unit of the type stated, adapted for use with refrigerator structures, to effect the cooling and heat control of the refrigerated compartment from the surrounding atmosphere, either with or without auxiliary power operated refrigerating equipment, whereby to increase the economy and efficiency of the refrigerating apparatus, enable decreased operating costs, and permit the use of smaller power units, if desired.

A still further object of the invention is to provide an automatic temperature control unit, to enable the use in refrigeration apparatus of the thermal cooling effects of the surrounding atmosphere, whereby to supplant or supplement such other cooling means as may be provided, such for example as ice, or power operated refrigeration means.

Various other objects, advantages and features of the invention will be apparent from the following specification when taken in connection with the accompanying drawings, wherein certain preferred embodiments are set forth for purposes of illustration.

In the drawings, wherein like reference numerals refer to like parts throughout:

Fig. 1 is a partial assembly view of a refrigerator structure, including a temperature control unit constructed in accordance with the principles of the invention, applied to the refrigeration space or chamber thereof;

Fig. 2 is a partial assembly view of a domestic refrigerator installation, incorporating the temperature control unit of the invention;

2

Fig. 3 is a longitudinal sectional view, on an enlarged scale, of the temperature control unit of Fig. 1;

Fig. 4 is a view similar to Fig. 3 but showing the valve members of the control unit in open position;

Fig. 5 is a transverse sectional view of the structure of Fig. 3 on the line 5—5 thereof;

Fig. 6 is a view similar to Figs. 3 and 4 but illustrating a modified form of the invention;

Fig. 7 is a transverse sectional view of the structure of Fig. 6 taken as indicated by the line 7—7 thereof; and

Fig. 8 is a view similar to Figs. 3, 4 and 6, but illustrating a still further modified form of structure.

In conventional refrigerator apparatus, ice, or power operated refrigeration means is used exclusively for controlling the temperature within the refrigeration space or compartment to be cooled. Such power operated refrigerating means may comprise an evaporator, condenser, refrigeration system, a brine circulating system, or air circulation system wherein the air is cooled by ice or other refrigeration means. In accordance with the present invention improved means is provided whereby the refrigeration effects of the atmosphere surrounding the refrigerator may be imparted to the compartment or refrigeration space to be cooled, whereby to supplant or supplement other cooling means which may be provided, such as ice, or power operated refrigeration mechanism, as stated.

Referring more particularly to the drawings, in Fig. 1, a corner portion of a refrigerator structure 10 is illustrated, having insulated walls 11 and 12, and a refrigeration compartment 13 to be cooled. The temperature control unit of the invention, generally indicated by the numeral 14, may be applied to a suitable portion of the refrigerator, for example the wall 11 as shown, and provides means whereby the refrigerating effects of the outside atmosphere surrounding the refrigerator may be imparted to the refrigeration space 13, in an automatic manner and in accordance with the temperature conditions prevailing in the refrigeration space and in the outside atmosphere. As will be seen, the temperature control unit extends through the refrigerator wall structure, one end communicating with the refrigeration space 13, the other end communicating with the outside atmosphere.

tion space 13, and the other end communicating with the outside atmosphere surrounding the refrigerator, for example as indicated by the numeral 15.

In Fig. 1 the refrigerator 10 may for example be a relatively large commercial installation wherein the walls 11 and 12 are contacted directly by the outside atmosphere on their exterior surfaces. In Fig. 2 an embodiment is illustrated wherein the invention is applied to an installation of the smaller household type. In this instance the refrigerator is generally indicated by the numeral 18, and comprises a body portion 19 and a hinged door portion 20 controlled by a handle 21 as will be understood. The refrigerator may be arranged within a room of a building or the like comprising outside walls 22, 23. It will be seen that in this instance the temperature control unit, generally indicated by the numeral 24, extends both through the building wall 22 and through the wall 25 of the refrigerator structure, so that one end thereof communicates with the refrigeration space or chamber 26 to be cooled, whereas the other end extends into and communicates with the outside atmosphere, in this instance indicated by the numeral 27.

The construction of the temperature control unit will be best understood by reference to Figs. 3, 4 and 5. A tube 30 extends through the wall separating the outside atmosphere and the refrigeration chamber or compartment to be cooled, for example the wall 11 as illustrated in Figs. 1 and 3. As will be understood, the tube 30 may comprise a pair of interfitted coaxial tube portions, as shown, press-fitted into the refrigerator wall structure. The two interfitted portions of the tube 30 are provided with outwardly turned flanges 31 and 32 at their ends. The flange 31, extending to the outside atmosphere, is secured to a pair of plate members 33 and 34 by means of a series of screws 35. The plate member 33, in the particular embodiment illustrated, is relatively flat and is provided with a series of openings 36 in annular spaced relation adjacent its central portion. The plate member 33 forms a valve seat for a valve member 37 adapted, when in closed position as shown in Fig. 3, to seat against the plate member and close the openings 36 whereby to prevent the transmission of fluids, such as air in the particular embodiment illustrated, through the tube 30.

The plate member 34 is of general cup shape, as shown, having a relatively flat central body portion 38, a cylindrical portion 39, and an outer flange portion secured by the screws 35. The cylindrical portion 39 of the plate is provided with a series of annularly spaced air passages or openings 40.

The body portion 38 of the plate member 34 is secured to the outer flange portion 42 of a second cup-shaped plate member, by suitable means such as welding as indicated at 43. This latter cup-shaped plate member has a cylindrical portion formed with a plurality of air passages or openings 44, and has a central body portion 45 to which one end of a gas-filled bellows 46 is suitably secured, as by welding, soldering or the like. The other or shiftable end of the bellows carries a shaft or valve stem 47 extending through central openings in the plate members 33 and 34, and carrying the valve member 37. The bellows 46 is sealed and carries a suitable temperature sensitive gas which is expanded upon a temperature increase, the bellows thus constituting a thermostat or temperature sensitive element,

operable to close the valve 37 against the valve plate or seat 33 when the atmosphere 15 to which the bellows is subjected is above a predetermined temperature. The openings 44 permit circulation of the atmospheric air around the bellows, so that the bellows is readily sensitive to the prevailing atmospheric temperature conditions.

A wire screen 49 is secured to the peripheral outer flange of the plate 33 and to the flange 42 of the outer cup-shaped member. It will be seen that when the valve 37 is in open position, as shown in Fig. 4, atmospheric air is free to circulate through the screen 49, through the openings 40 of the plate 34, and through the openings 36 of the valve plate or seat member 33 into and through the tube 30.

The temperature control unit is similarly constructed at its opposite end which extends into the refrigeration compartment 13 to be cooled, with the exception that the operable valve member is in this instance arranged to be opened when the temperature in the compartment 13 rises above a predetermined value. More particularly, the tube flange 32 is secured to a pair of plate members 51 and 52 similar in structure and purpose to the plate members 33 and 34 previously described. To this end the plate member 51 is provided with circumferentially disposed central openings 53 cooperable with the shiftable control valve member 54, whereas the cup-shaped plate member 52 provides a support for a second cup-shaped plate member 55 within which is secured the expansible bellows 56. The cup member 55 is provided with side wall openings 57, similar in function and purpose to the openings 44 previously described, so that the bellows is subjected to the temperature of the air within the refrigerated compartment 13. The bellows 56 is sealed, and provided with a temperature sensitive gas which expands upon increase in temperature. The free end of the bellows carries a stem 58 upon which the valve member 54 is secured. It will be seen that when the temperature in the compartment 13 raises beyond a predetermined value, the valve member 54 is shifted away from its seat plate or to open position as shown in Fig. 4. When the valve is open air may circulate from the tube 30 through the valve plate openings 53, openings 59 provided in the plate member 52, and the cylindrical screen member 60 into the refrigerated compartment 13. As will be understood, the screens 49 and 60 prevent the flow of any foreign matter from the atmosphere into the refrigerated compartment.

In the operation of the structure, let it be assumed that the temperature of the refrigerated compartment is to be maintained between 50° F. and 55° F. The bellows 46 will accordingly be so constructed, and the parts so arranged, that the valve 37 will be shifted from closed position as shown in Fig. 3, to open position as shown in Fig. 4 when the temperature drops to or below 55°. In other words, the bellows 46 will be contracted sufficiently to open the valve whenever the temperature of the outside atmosphere is at or below 55°. The bellows 56 and its associated parts will be arranged so that the valve member 54 will be shifted from closed position as shown in Fig. 3 to open position as shown in Fig. 4 whenever the temperature of the refrigerated compartment 13 rises above 50°. In other words, the gas within the bellows is expanded sufficiently to open the valve whenever the temperature within the refrigerated compartment 13 is at or above 50°. It will thus be seen that whenever the temperature of the outside atmosphere is below 55°, or pos-

sesed of the desired cooling capacities, and if the temperature of the refrigerated compartment 13 is above 50°, both valve members 37 and 54 will be opened and the cooling effects of the atmosphere may be transmitted into the refrigerated compartment by the circulation of air from the atmosphere into the compartment. However, should the temperature of the outside atmosphere rise above 55°, so that it is no longer possessed of the desired cooling properties, valve 37 will close; or should the temperature within the refrigerated compartment drop below 50°, so that cooling thereof is no longer desired, valve 54 will close; the closing of either valve being sufficient to prevent further circulation of air between the atmosphere and the refrigerated chamber.

It will thus be seen that automatic means is provided, controlled in accordance with the temperature conditions of the outside atmosphere and of the compartment to be refrigerated, so that the cooling effects of the atmosphere may be utilized, automatically, whenever the atmosphere is possessed of the desired cooling properties and the refrigerated compartment requires cooling. There is no danger of heat loss to the outside atmosphere, when the temperature thereof becomes too warm, nor is there any possibility of the refrigerated compartment being unduly cooled, and the articles therein unduly chilled or frozen. It is to be understood that the temperatures referred to are illustrative only, and may be selected in accordance with the requirements of any particular installation.

It will be seen that the temperature control unit, where atmosphere conditions are suitable, may be used as the sole cooling means for the compartment to be refrigerated; or it may be used as an auxiliary to ice, or other artificial or mechanical cooling means provided for the refrigerated chamber. When used as an auxiliary to artificial cooling means provided, the temperature control unit of the invention in no way interferes with the operation thereof. On the contrary it operates automatically to supplement the artificial refrigeration with the cooling effects of the atmosphere, whenever conditions are suitable. The cooling requirements of the artificial means are thus reduced permitting the use of smaller cooling capacities, and increasing economy and efficiency.

The outside atmosphere 15 may in effect be regarded as a second chamber, automatically placed in communication with the refrigerated chamber 13, when temperature conditions within the two chambers, individually, are in predetermined condition.

In certain instances it may be desirable to provide forced draft circulation means, automatically controlled, so as to be energized whenever both valves are open. Such means is illustrated in Figs. 3 and 4. A spider support 65 is disposed within the tube 30 for supporting an electric motor 66 which operates an air fan 67. A switch 68 is secured to the valve stem 47 operable to engage the cooperable fixed switch contact 69, whenever the valve member 37 reaches predetermined open position. Similarly a switch contact 70 secured to the valve stem 58 is adapted to engage a co-operable fixed switch contact 71 when the valve 54 moves to a predetermined open position. These switches are connected in series in a control circuit (not shown) for energizing the motor 66. It will be seen that when both valves are open the motor 66 is energized and the fan 67 operated to provide a forced air circulation from the out-

side atmosphere into the refrigerated compartment. When such forced draft means is provided, it may be desirable to provide a suitable exhaust check valve as indicated at 72 in Fig. 1 and at 73 in Fig. 2, so as to permit air exhaust from the refrigerated compartment; or, if desired, two temperature control units, having inlet and outlet exhaust fans, may be provided.

In Figs. 6 and 7 a modified embodiment is illustrated generally similar to that shown in Figs. 3 and 4 except that snap or quick action operating means is provided for shifting the control valve members. In this instance the tube member 30a, corresponding in function and purpose to the tube 30 previously described, is secured at one end to a valve seat plate 33a and to cup-shaped plate members 34a and 45a as in the embodiment previously described. However, in this instance the bellows 46a carries a stem 75 to which is secured an operating arm 76 of general L-shape and being axially shiftable, as the bellows is expanded, between a pair of turned guiding projections 77 and 78, Fig. 7, struck inwardly from the wall portion 39a of the plate cup member 34a. An operating lever 79 is pivotally connected at one end to the projection 78 and at its other end to the valve stem 47a. A tension spring 80 is connected at one end to the operating arm 76 and at its other end to a mid-point of the lever 79. It will be seen that when the bellows 46a has expanded a predetermined amount from the position shown, the operating arm 76 will be carried downwardly sufficiently to move the outer end of the spring downwardly past the outer pivot point 81 of the lever 79, whereupon the valve 37a will be closed with a snap action. The valve will be opened with a snap action in a similar manner upon contraction of the bellows. A collar 82 carried by the valve stem 47a limits the opening movement of the valve. Similar operating mechanism may be provided for the valve 54a, except that the latter opens inwardly, as in the case of the valve 54 previously described.

Quick acting valve operating mechanism as illustrated in Figs. 6 and 7 may in certain instances be desired. It will be seen that in this instance there will be a predetermined temperature differential between the opening of the valves, and the closing thereof, which may be made of greater or lesser magnitude by the spacing of the parts, in reference to the expanding movements of the bellows.

In Fig. 8 an embodiment is illustrated incorporating electrical operating mechanism. In this instance the valve 37b has its stem 47b elongated for cooperation with a pair of electromagnets 85 and 86. The electromagnet 85 is operable, when energized, upon a suitable armature secured to the valve stem, so as to shift the valve to closed position. The electromagnet 86 is similarly operable when energized to shift the valve member to open position. The bellows 46b is arranged to operate a switch member 87 arranged to bridge switch contacts 88 when in predetermined contracted position as shown, and to bridge a pair of contacts 89 when expanded to a predetermined position. A switch member 90, secured to the valve stem 47, is adapted selectively to engage either of a pair of contacts 91 and 92 as the valve stem is shifted. The valve stem also carries a cam 93, the pointed end of which is adapted to engage a frame carried ball detent 94, spring urged into engagement with the cam by means of 75 a compression spring 95.

In operation, and assuming the valve 37b to be in open position, it will be seen that a predetermined expanding movement of the bellows 46b will cause the bridging of the contacts 89. This causes the closing of an electrical circuit from line L₁ through the contacts 89, through the electromagnet 85, and through contacts 91 and 90 to line L₂. The energization of electromagnet 85 causes the shifting of the valve toward closed position. As the contact 90 is shifted away from the contact 91, the energizing circuit is broken. However, the circuit is not broken until after the mid-point of the cam 93 has been shifted below the spring pressed detent ball 94, so that the ball completes the shifting of the valve to fully closed position. To open the valve it will be seen that upon a predetermined contraction of the bellows the contacts 88 are bridged thus energizing the electromagnet 86 through the contacts 92 and 90. After the valve stem has been moved sufficiently by the electromagnet to raise the center of the cam 93 past the ball 94, contacts 92, 90 are broken de-energizing the electromagnet, and the detent ball completes the valve shifting movement. Similar operating mechanism is provided for the valve 54b, except that the valve opens inwardly, as previously described.

It is obvious that various changes may be made in the specific embodiments set forth for purposes of illustration without departing from the spirit of the invention. Accordingly the invention is not to be limited to the specific embodiments set forth, but only as indicated in the following claims.

The invention is hereby claimed as follows:

1. A temperature control unit for controlling the temperature of at least one of a pair of thermally isolated fluid containing spaces comprising a first valve member, means associated with one of said spaces for operating the valve member in accordance with the temperature in said space, a second valve member, means associated with the other of said spaces for operating the second valve member in accordance with the temperature in said other space, a passageway connecting said spaces controlled by said valves, the flow of fluid within said passageway being blocked by the closing of either of said valves, fluid pumping means for propelling a heat conducting fluid through said passageway, and means operated by the opening of both of the valve members to energize the pumping means.

2. A temperature control unit for controlling the temperature of at least one of a pair of thermally isolated fluid containing spaces comprising

a first valve member, means associated with one of said spaces for opening the valve member when the temperature in said space is above a predetermined value, a second valve member, means associated with the other of said spaces for opening the second valve member when the temperature in said other space is below a predetermined value, a passageway connecting said spaces controlled by said valves, the flow of fluid within said passageway being blocked by the closing of either of said valves, the first named predetermined temperature being no greater than the second named predetermined temperature, fluid pumping means for propelling a heat conducting fluid through said passageway, and means operated by the opening of both of the valve members to energize the pumping means.

3. A temperature control unit for controlling the temperature between predetermined limits of one of a pair of thermally isolated fluid containing spaces by means of temperature conditions in the other of said spaces comprising a first valve member, means associated with one of said spaces for opening said valve member when the temperature in said space is above one limit of the desired temperature range within the space to be controlled, a second valve member, means associated with the other of said spaces for opening the second valve member when the temperature in said space is below the other limit of the desired temperature range within the space to be controlled, a passageway connecting said spaces controlled by said valve members, the flow of fluid within said passageway being blocked by the closing of either of said valves, electrically driven fluid pumping means for propelling a heat conducting fluid through said passageway, and switch members operated by the opening of both of said valve members to energize the pumping means.
